Amos Paul of South New Market N. H.
Letters Patent No. 304. Dated July 22. 1850

The Schedule referred to in these Letters Patent and making part of the same.

To all Persons to whom these Presents shall come:

Be it Known that

I, Amos Paul of South New Market, in the County of Rockingham, and State of New Hampshire, have invented or produced a new and useful design for the front plate of a portable grate, and I do hereby declare that the said new design is fully described and represented in the following specification and accompanying drawings, to which reference is hereinafter made.

Of the drawings Fig. 1 is an elevation of said plate, Figs. 2 & 3 are sections taken on the lines AB & CD Fig. 1, respectively.

My new design consists of a five centred arch, moulding, a a a a on the horizontal part of the three sided frame or plate, with concentric ledges or steps as shown at b b &c. said arch being sustained at each end, on the triple column pilaster cc-cc having a proper cap d, and base e, all cast in alto relief on the vertical parts of the frame; the bases of the pilasters resting on the plinths f f. The space under the arch moulding a a a is filled with a series of radial wedge shaped ribs g g g &c, proceeding from the cluster of crescent shaped steps h h h. On each side of each triple column pilaster, is a sunken gothic panel i. i. i. i. i. i.

On the top of the moulding a a a is the plain tablet k k, on each side of this tablet, and in each upper corner of the horizontal part of the frame is a three sided sunken panel having the stepped or recessed moulding l l l. l l l and with the wedge shaped radial ribs m m m &c.

Having thus described my new design I shall state my claim as follows.

What I claim as my invention or production, and

Des. 304

383

desire to have secured to me by Letters Patent, is the new design herein above described for the front plate of a portable grate, consisting of the five centred arch moulding, supported by the triple column pilasters, in combination with the gothic panels on each side of said pilaster, and three-sided panels on the horizontal part of the frame; said three-sided panels and the space beneath the arch moulding, being filled with the wedge shaped radial ribs, all as herein above described.

Witnesses.

End I. C. Skinner
C. E. & Wm L. Walker }
